(57) **ABSTRACT**

A new *Salvia* plant named 'Mes Ros,' particularly distinguished by red-purple flower color, upright, well branched, dense and bushy habit, medium green foliage and large sized flowers that are early flowering.

1 Drawing Sheet

1

Latin name of the genus and species of the plant claimed:
Salvia×hybrid.

Varietal denomination: 'Mes Ros'.

BACKGROUND OF THE NEW PLANT

The present invention comprises a new *Salvia*, botanically known as *Salvia*×hybrid, and hereinafter referred to by the variety name 'Mes Ros.'

'Mes Ros' is a product of a planned breeding program. The new cultivar 'Mes Ros' has red-purple flower color, upright, well branched, dense and bushy habit, medium green foliage and large sized flowers that are early flowering.

'Mes Ros' originated from an open pollination cross in a controlled breeding program in Gilroy, Calif. USA. The female parent was an unpatented, proprietary hybrid seedling (*S. greggii*×*microphylla*) identified as '156-1' with raspberry color. '156-1' has fewer flowers, larger foliage, and a taller plant habit than 'Mes Ros.' The male parent of 'Mes Ros' was unknown.

'Mes Ros' was selected as one flowering plant within the progeny of the stated cross in September 2005 in a controlled environment in Gilroy, Calif. USA. The pollination took place in July 2004 and the seed sowing in May 2005.

The first act of asexual reproduction of 'Mes Ros' was accomplished when vegetative cuttings were taken from the initial selection in the September 2005 in a controlled environment in Gilroy, Calif. USA.

Horticultural examination of plants grown from cuttings of the plant initiated in September 2005 in Gilroy, Calif. USA, and continuing thereafter, has demonstrated that the combination of characteristics as herein disclosed for 'Mes Ros' are firmly fixed and are retained through successive generations of asexual reproduction.

'Mes Ros' has not been observed under all possible environmental conditions. The phenotype may vary significantly with variations in environment such as temperature, light intensity and day length.

A Plant Breeder's Right for this cultivar was applied for in Canada on Dec. 24, 2007. 'Mes Ros' has not been made publicly available more than one year prior to the filing of this application.

2

DESCRIPTION OF THE DRAWINGS

The accompanying photographic drawing shows typical flower and foliage characteristics of 'Mes Ros' with colors being as true as possible with an illustration of this type.

The photographic drawing shows two flowering potted plants of the new variety and a close-up of the flowers, growing in a one gallon pot.

This plant was grown and photographed in Gilroy, Calif. USA in April 2008. The plant was about 4 months old.

DETAILED BOTANICAL DESCRIPTION

The measurements were taken on plants growing in Gilroy, Calif. USA in April 2008. The plants were growing in gallon pots in a greenhouse trial. These plants were about 4–5 months old.

Color Chart used: Royal Horticultural Society Colour Chart (R.H.S.) 2001

BRIEF SUMMARY OF INVENTION

The following observations, measurements, and comparisons describe plants grown Gilroy, Calif. USA. The following traits have been repeatedly observed and are determined to be basic characteristics of the new variety. The combination of these characteristics distinguishes this *Salvia* as a new and distinct variety.

TABLE 1

DIFFERENCES BETWEEN THE NEW CULTIVAR 'MES ROS' AND A SIMILAR VARIETY			
	'Mes Ros'	'Navajo Rose'	
35	Floriferousness Foliation size Plant habit	More flowers Larger More compact	Less flowers Smaller Less compact

Plant:

Form, growth and habit.—Upright, well branching, dense and bushy.
Plant height.—28–31 cm.
Plant height (inflorescence included).—39–42 cm.
Plant width.—30–35 cm.

40

Foliation:

Type.—Simple, opposite.	Width of upper lip.—0.3–0.4 cm.
Immature, leaf color, upper surface.—Closest to RHS 146B.	Shape.—Obovate.
Lower surface.—Closest to RHS 147B.	Apex shape.—Obtuse.
Mature, leaf color, upper surface.—Closest to RHS 146A.	Margin.—Entire.
Lower surface.—Closest to RHS 147B.	Texture, outer surface.—Papillose; villous hairs of RHS 66A at the apex.
Length.—4.2–5.4 cm.	Inner surface.—Glabrous.
Width.—2.4–2.7 cm.	Color lower lip, mid-lobe, upper surface.—RHS N57A.
Shape.—Ovate.	Color lower lip, mid-lobe, lower surface.—RHS 67A.
Base shape.—Attenuate.	Length of lower lip, mid-lobe.—1.3–1.4 cm.
Apex shape.—Obtuse to slightly acute.	Width of lower lip, mid-lobe.—1.2–1.3 cm.
Margin.—Crenulate.	Shape.—Obcordate.
Texture, upper surface.—Muriculate.	Apex shape.—Emarginate.
Texture, lower surface.—Muriculate.	Margin.—Appears very slightly laciniate.
Fragrant.—Heavily “sage” like.	Texture, upper surface.—Papillose.
Color of veins, upper surface.—RHS 144A.	Lower surface.—Glabrous and slightly hispid.
Color of veins, lower surface.—RHS 144A.	Color lower lip, lateral lobe, upper surface.—RHS N57B.
Petioles color.—RHS 144A.	Color lower lip, lateral lobe, lower surface.—RHS 67A.
Petioles length.—0.7–1.4 cm.	Length of lower lip, lateral lobe.—0.6 cm.
Diameter of petiole.—0.1 cm.	Width of lower lip, lateral lobe.—0.3 cm.
Texture.—Hispid.	Petal shape.—Oblong.

Stem:

Number of main branches per plant.—3–4.	Apex shape.—Obtuse.
Number of leaves per stem.—12–16.	Margin.—Entire.
Color of stem.—RHS 146C.	Texture, upper surface.—Papillose.
Length of stem.—25–30 cm.	Lower surface.—Glabrous.
Diameter.—0.3 cm.	Corolla, color, outer surface.—RHS 67A.
Length of internodes.—2–3 cm.	Inner surface.—RHS 55B but RHS N155B stripes.
Texture.—Hispid.	Length of corolla.—1.5 cm.

Inflorescence:

Type.—Terminal raceme.	Width of corolla.—0.7 cm at the widest.
Blooming habit.—Flowers continuously from spring through the fall.	Texture, outer upper surface.—Slightly hispid.
Number of racemes per plant.—35–40.	Texture, outer lower surface.—Glabrous.
Duration of flowering.—Continuous flowering throughout the summer.	Texture, inner surfaces.—Glabrous.
Color of peduncle.—RHS 146C.	Bud (just before opening):
Length of peduncle.—8–16 cm.	Color.—RHS 71A.
Peduncle diameter.—0.1–0.15 cm.	Length.—1.0–1.2 cm.
Texture.—Hispid; glandular hairs.	Width.—0.3–0.4 cm.
Color of pedicel.—RHS 146D.	Shape.—Tubular to oblong.
Length of pedicel.—0.3–0.4 cm.	Calyx:
Diameter of pedicel.—0.1 cm.	Number of sepals.—2, fused into a tube form.
Texture.—Hispid.	Color of sepals, upper surface, upper most sepal.—RHS 144C ground color; RHS 176A stripes of anthocyanins.

Corolla:

Form.—Single, bilabiate; with one upper lip, with one lower lip with three lobes consisting one a mid-lobe and 2 small lateral lobes; fused at base; upper lip wraps around the pistil.	Lower most sepals.—RHS 144C ground color; RHS 176A at the apex.
Lastingness of individual bloom on the plant.—5–6 days.	Inner surface of all sepals.—RHS 147C.
Fragrance.—“Sage” like.	Length of sepals.—1.0–1.1 cm.
Immature florets general color, upper surface.—Closest to RHS N57A but deeper.	Width of sepals.—0.2–0.4 cm.
Lower surface.—RHS 67A.	Sepal shape.—Broadly linear.
Mature florets vertical height of floret.—1.8–2.0 cm.	Apex shape.—Acute.
Horizontal width of floret.—1.8–2.0 cm.	Margin.—Entire.
Depth of floret.—2.4–2.5 cm.	Texture, outer surface.—Hispid.
Color upper lip, upper surface.—Closest to RHS N57B but appears brighter because of the RHS N66A color of the villous hairs.	Inner surface.—Glabrous.
Color upper lip, lower surface.—RHS 67A.	Reproductive organs:
Length of upper lip.—0.8–0.9 cm.	Pistil.—1.
	Length.—2.5 cm.
	Style color.—RHS N155B but whiter.
	Style length.—2.1–2.3 cm.
	Stigma color.—RHS 77D.
	Stamens.—2.
	Color of filaments.—RHS N155B but whiter.
	Length of filaments.—1.1 cm.
	Anther color.—RHS 15A.
	Anther length.—0.15–0.2 cm.

US PP20,707 P2

5

Color of pollen.—RHS 17B.

Pollen amount.—Moderate.

Fertility/seed set.—Not observed on this hybrid.

Disease/pest resistance: Disease resistance or susceptibility
has not been observed on this hybrid.

6

What is claimed is:

1. A new and distinct variety of *Salvia* plant named 'Mes
Ros,' substantially as illustrated and described herein.
